UNITED STATES PATENT OFFICE.

EDWARD B. MANNING AND MICHAEL SEIPS, OF MERIDEN, CONNECTICUT.

DESIGN FOR A HANDLE FOR TEA OR COFFEE POTS.

SPECIFICATION forming part of Design No. 27,907, dated November 30, 1897.

Application filed October 18, 1897. Serial No. 655,634. Term of patent 14 years.

To all whom it may concern:

Be it known that we, EDWARD B. MANNING and MICHAEL SEIPS, of Meriden, in the county of New Haven and State of Connecticut, have 5 invented a new Design for Handles for Tea or Coffee Pots, &c.; and we do hereby declare the following, when taken in connection with the accompanying drawing and the letters of reference marked thereon, to be a full, clear, 10 and exact description of the same, and which said drawing constitutes part of this specification and represents a perspective view of a handle embodying our design.

This invention relates to a design for handles for tea and coffee pots and kindred vessels; and it consists in the configuration hereinafter described, and shown in the accompanying illustration.

As herein shown, the design consists of a handle A, oval in general form, and a single 20 plate B, into the upper and lower edges of which the upper and lower ends of the handle merge.

We claim—

The design for a handle for tea and coffee 25 pots as shown in the accompanying illustration.

In testimony whereof we have signed this specification in the presence of two subscribing witnesses.

EDWARD B. MANNING.
MICHAEL SEIPS.
